HOSE COUPLING

Filed Nov. 26, 1930

Inventor
Cassius M. Clay Baird
Rummel, Rummel
Woodworth Atty's:

UNITED STATES PATENT OFFICE

CASSIUS M. CLAY BAIRD, OF EVANSTON, ILLINOIS

DESIGN FOR A HOSE COUPLING

Application filed November 26, 1930. Serial No. 37,796. Term of patent 3½ years.

To all whom it may concern:

Be it known that I, CASSIUS M. CLAY BAIRD, a citizen of the United States, residing at Evanston, in the county of Cook and State of Illinois, have invented a new, original, and ornamental Design for a Hose Coupling, of which the following is a specification, reference being had to the accompanying drawing, forming part thereof.

The figure is a perspective view of a hose coupling showing my new design.

I claim:

The ornamental design for a hose coupling as shown.

CASSIUS M. CLAY BAIRD.
